RESILIENT EXPANDED PLASTIC BOAT FENDER OR THE LIKE

Jack L. Simpton, 4632 Redwood Ave., and Robert E. Seitz, 5228 Emory Circle, both of Jacksonville, Fla. 32207

Filed Nov. 5, 1969, Ser. No. 19,947

Term of patent 14 years

Int. Cl. D12—14

U.S. Cl. D71—1

FIG. 1

FIG. 5

FIG. 4

FIG. 3

FIG. 2

FIG. 1 is a rear perspective view of the resilient expanded plastic boat fender or the like in accord with our new design;

FIG. 2 is a side elevational view thereof;

FIG. 3 is a side elevational view thereof;

FIG. 4 is a front elevational view thereof; and

FIG. 5 is a cross-sectional view taken along line 5—5 of FIG. 4.

We claim:

A resilient expanded plastic boat fender or the like, substantially as shown.
